UNITED STATES PATENT OFFICE.

LORENZO R. HAYWOOD, OF BIRMINGHAM, ALABAMA.

SHOE AND BOOT POLISHING MACHINE.

Application filed May 19, 1922. Serial No. 582,221.

To all whom it may concern:

Be it known that LORENZO R. HAYWOOD, a citizen of the United States of America, residing at Birmingham, in the county of 5 Jefferson and State of Alabama, has invented new and useful Improvements in Shoe and Boot Polishing Machines, of which the following is a specification.

The object of the invention is to provide 10 an efficient mechanical means for cleaning, applying blacking, paste or dressing and finally polishing shoes or boots, under conditions serving to economize in the application of the blacking or other polishing material to the same; and furthermore under 15 conditions providing for the coin control of the mechanism, to the end that the apparatus may be set up for operation without requiring the presence of an attendant; 20 and with these objects in view the invention consists in a construction and combination of parts of which a preferred embodiment is shown in the accompanying drawings, wherein:—

25 Figure 1 is a perspective view of a polishing machine constructed in accordance with the invention.

Figure 2 is a plan view of the same with the top or upper wall of the same omitted.

30 Figure 3 is a longitudinal sectional view on the plane indicated by the line 3—3 of Figure 2.

Figures 4, 5 and 6 are transverse sectional views respectively on the planes indicated by the lines 4—4, 5—5 and 6—6 of Figure 3.

35 Figure 7 is a longitudinal sectional view on the plane taken by the line 7—7 of Figure 2.

40 Figure 8 is a detail view in perspective of the cam actuated clutch shifting mechanism.

Figure 9 is a detail view of the timing gears.

45 The casing 10 is provided with suitable openings 11 to permit of the insertion of the shoes or boots to enable the wearer to position the feet successively upon the stands or rests 12 arranged respectively in relation to stations A, B and C which are designed

50 for successive treatment of a shoe or boot and are adapted respectively for cleansing or applying a liquid dressing to the shoes, for applying a polish or paste to the shoes and finally for polishing the surface which 55 has previously been treated with the paste.

The cleansing unit at A preferably con-

sists of the opposed side rotary brushes 13 having their spindles mounted upon suitable pedestals 14 and with their bristles arranged in frictional contact with endless distributing belts 15 extending around rollers 16 and 17 of which the latter are arranged in receptacles such as the troughs 18 designed to contain a cleansing liquid or dressing in a liquid form to be applied primarily to the leather of the shoe for removing dust and softening the leather in preparation for the application of a paste or like dressing. The belts dipping into and passing through the liquid contents of the troughs carry the material to the bristles of the brushes which thereupon apply the same to the shoe or boot occupying the stand or rest 12 which is located in an intermediate relation with the brushes.

At the station B representing the polish applying unit of the mechanism there are arranged the side brushes 19 having their spindles mounted in the pedestals 20 and with their bristles in contact with distributing brushes 21 which operate in receptacles 22 designed to be supplied with a suitable paste either black, tan or otherwise according to the preferred equipment of the mechanism, said distributing brushes designed to be rotated by the contact therewith of the main brushes 19 and to convey the paste to the bristles of the latter for application to the boot or shoe occupying the immediate stand or rest.

90 The polishing unit represented at station C includes the axially vertical side brushes 22' and the axially horizontal toe and heel brushes 23 and 24 adapted to operate respectively in relatively elevated and depressed positions with relation to the foot stand or rest so as to operate on the upper surface of the vamp and on the back or counter and heel of the shoe to effect a proper and uniform polishing thereof.

100 In the construction illustrated, the means for operating the several elements of the polishing mechanism consists of a main shaft 25 driven, for example, by a motor 26, and countershafts 28 driven from the main shaft by gears 29 and 30, the former floating upon the main shaft and being operatively engageable therewith by means of clutches 27 keyed to but slidably upon the main shaft. The spindles of the main brushes of both the cleaning and polish applying units carry bevel gears 31 meshing

with similar gears 32 on the countershafts, and preferably the distributing elements consisting of the belts 15 and brushes 21 are likewise positively driven from the counter-shafts through gears 33 and 34 with the intermediate idlers 35 as shown in Figure 7.

The axially vertical brushes 22' of the polishing unit may be driven through a countershaft 36 geared as at 37 to the main shaft and to the spindles of the said brushes by the bevel gears 38 indicated in Figure 3 while the axially horizontal front and rear brushes of said polishing unit may have their spindles connected for simultaneous movement by the chain 39 traversing sprocket wheels 40, and may receive motion through a chain 41 directly from the drive shaft 25 through the sprocket wheels 42.

It is desirable to have the mechanism controlled by means which can be released by the deposit of a coin, and to this end a coin chute 43 is arranged in operative relation with the path of a push rod 44 yieldingly held in its retracted position by a spring 45 and carrying a follower 46 which cooperates with a similar follower 47 on a trip rod 48, said followers being arranged to operate in conjunction with a shelf 49 which serves to check the downward movement of a coin 30 dropped into the chute until pressure is applied to the push rod to advance the trip rod. The trip rod is connected with a switch arm 50 carrying one element of a knife switch 51 adapted to be closed by the actuation of the push rod when a coin has previously been positioned between the follower heads. In the construction illustrated as will be noted by reference to Figure 3 the follower head 46 is divided to provide elements operating in planes at opposite sides of the plane of the follower head 47, so that if the push rod is actuated without having previously deposited a coin the motion thereof has not been communicated to the trip rod. 45 The switch arm 50 is connected by means of a link 52 with a shifting block 53 having shoulders arranged in the path of movement in opposite directions of a shifting arm 54 forming part of a bell crank lever 55 which is 50 connected by a link 56, as shown clearly in Figure 8 with a shifting lever 57 arranged terminally in operative relation with a cam 58. This shifting lever is of bell-crank form and is connected by a link 59 with a clutch yoke 60 adapted to shift the clutch by which motion is communicated from the drive shaft to the elements of the cleansing unit at the station A. The cam 58 which is carried by the shaft 61 also operates in connection with 55 a shifting lever 57a also of the bell-crank type connected by a link 59a with the clutch yoke 60a which operates to shift the clutch by which motion is communicated to the polish applying unit at station B. The cam shaft 61 receives its motion from the drive

shaft 25 through timing mechanism having a train of gears 62 receiving motion through a worm 63 on the drive shaft to the end that after the mechanism has been started by the closing of the switch 51, it will operate for a distinct length of time determinable by the timing mechanism when the clutches will be successively shifted to disconnect the units A and B (the latter a predetermined interval after the former) while permitting the polishing unit to continue its operation until the extremity of the cam surface is reached and the end of the lever 57 drops toward the center of the cam to thereby swing the shifting arm 54 and thereupon the shifting block 53 in a direction to open the switch 51 and thereby stop the motor. This movement of the parts permits the closing of the clutches 27 by the actuating springs 27a provided in that connection.

Having described the invention, what is claimed as new and useful is:—

1. A machine for the purpose indicated having in combination with a motor actuable drive shaft a plurality of shoe treating units provided with rotary brushes, clutches for controlling the communication of motion from the drive shaft to the brushes of the said units, clutch shifting mechanism, and a cam actuating timing mechanism actuable by the drive shaft for controlling the clutch shifting mechanism.

2. A shoe polishing apparatus having a motor actuated drive shaft, polish applying and polishing units having rotary elements for actuation by said drive shaft, clutch mechanism for controlling the communication of motion from the drive shaft to the polish applying units, a switch for controlling the motor circuit, coin controlled manually operable switch closing means, switch opening means, and a cam operated by and in timed relation with the drive shaft for successively actuating said clutch mechanism and said switch opening means.

3. A shoe polishing apparatus having a motor actuated drive shaft, cleaning, polish applying and polishing units having rotary elements for actuation by said drive shaft, clutch mechanism for controlling the communication of motion from the drive shaft to the cleaning and polish applying units, a switch for controlling the motor circuit, coin controlled manually operable switch closing means, switch opening means, and a cam operated by and in timed relation with the drive shaft for actuating the clutch mechanism to release first the cleaning unit and then the polish applying unit at a predetermined interval thereafter, and finally actuate the switch opening means.

In testimony whereof he affixes his signature.

LORENZO R. HAYWOOD.
